DESIGN FOR A PENHOLDER DESK UNIT OR SIMILAR ARTICLE

Thomas Hill, New York, N. Y.

Application February 28, 1935, Serial No. 55,650

Term of patent 3½ years

To all whom it may concern:

Be it known that I, Thomas Hill, a citizen of the United States, residing in New York city, in the county and State of New York, have invented a new, original, and ornamental Design for a Penholder Desk Unit or Similar Article, of which the following is a specification, reference being had to the accompanying drawing, forming a part thereof, and of which Figure 1 is a view in front elevation; Fig. 2 is a view in side elevation; and Fig. 3 is an inverted view in side elevation of

the device, showing my new design in position to be attached to the side of an inkwell or other article.

The various elements shown are integral parts of a unitary design.

I claim:

The ornamental design for a penholder desk unit or similar article substantially as shown and described.

THOMAS HILL.
